UNITED STATES PATENT OFFICE.

PHILIP MICHEL, OF STAPLETON, NEW YORK.

WINDOW-SHADE.

SPECIFICATION forming part of Letters Patent No. 241,689, dated May 17, 1881.

Application filed March 25, 1881. (No model.)

To all whom it may concern:

Be it known that I, PHILIP MICHEL, a citizen of the United States, residing at Stapleton, in the county of Richmond and State of New York, 5 have invented new and useful Improvements in Window-Shades, of which the following is a specification.

This invention consists in a metallic binding-strip provided with two folds, one embracing the edge of the shade and the other embracing the edge of a pendent trimming to produce a facile connection of such trimming with the shade.

This invention is illustrated in the accompanying drawings, in which Figure 1 represents a front view. Fig. 2 is a cross-section on a larger scale than the previous figure.

Similar letters indicate corresponding parts.

The letter A designates the shade, B the binding-strip, and C the trimming. The shade A and trimming C are made of any usual or suitable materials, and the binding-strip B is bent lengthwise to conform to the shape of the lower edge of the shade, this edge being in this example cut to an ornamental shape. The binding-strip B is formed of sheet metal, and with a double fold, *d e*, in cross-section, the fold *d* opening in an upper direction and embracing the edge of the shade A, while the fold *e* opens 20 in a lower direction and embraces the edge of the trimming C, so that the latter occupies the required pendent position.

In applying the strip B the edges of the shade and trimming, respectively, are inserted in the folds *d e*, and then the folds are compressed or flattened—as, for instance, by pressing the whole between pressing-rollers, the parts being thus firmly connected together. 35

It will be perceived that the metallic binding-strip B serves to protect the lower edge of the shade, and also to impart thereto the required rigidity and weight, thus taking the place of the slat usually employed for this purpose, while by the double fold of the strip an extremely facile connection of the trimming 40 with the shade is produced, the result of which is that the cost of the shade is reduced to a minimum. 45

What I claim as new, and desire to secure by Letters Patent, is—

The combination, substantially as hereinbefore set forth, of the shade, the metallic binding-strip formed with a double fold, and the pendent trimming, for the purpose specified. 50

In testimony whereof I have hereunto set 55 my hand and seal in the presence of two subscribing witnesses.

PHILIP MICHEL. [L. S.]
